UNITED STATES PATENT OFFICE.

NILS A. LYBECK, OF KEARNEY, NEBRASKA.

GLASS-CUTTING DEVICE.

No. 849,149.

Specification of Letters Patent.

Patented April 2, 1907.

Application filed June 9, 1906. Serial No. 321,011.

To all whom it may concern:

Be it known that I, NILS A. LYBECK, a citizen of the United States, residing at Kearney, in the county of Buffalo and State of Nebraska, have invented new and useful Improvements in Glass - Cutting Devices, of which the following is a specification.

This invention relates to glass-cutting devices designed especially for use in decapping bottles, and has for its objects to produce a comparatively simple inexpensive device of this character which may in practice be conveniently operated and one whereby the bottle-neck or other tubular glass element 15 may be readily and effectually cut.

With these and other objects in view the invention comprises the novel features of construction and combination of parts more fully hereinafter described.

20 In the accompanying drawings, Figure 1 is a perspective view of a glass-cutting device, showing one form of embodiment of the invention. Fig. 2 is a side elevation showing another form of embodiment of the invention.

25 Referring to the drawings, and particularly to Fig. 1, 1 designates a base-plate, preferably of the form shown and adapted for attachment to a table or other support by means of screws or like fastening members, which may be entered through openings or 30 perforations 2, provided in the plate, on which there is fixed a vertically-uprising guide member 3, having a longitudinal guide 35 opening or slot 4, there being disposed at a point in advance and suitably remote from the guide 3 a pair of spaced bearings 5, in which are rotatably mounted glass-cutting elements or diamonds 6, the arrangement

40 being such that the diamonds are maintained in spaced relation, but in accurate alinement with each other. Pivoted at its rear end, as at 7, between bearing-ears 8 on the plate is an adjustable member or lever 9, disposed 45 for movement between its ends in the guide-slot 4, the member, which is adapted for vertical movement and normally maintained in elevated condition by means of a U-shaped spring 10, being provided at a point in advance of the guide 3 with a bearing 11, in

50 which is journaled a rotary glass-cutting element or diamond 12, corresponding in form and operation with the coöperating elements 6.

In practice the bottle-neck or other tubular glass element to be acted upon is seated on the cutting elements 6, after which the adjustable member 9 is moved downward until the cutting member 12 comes into contact with the work, after which the latter is 55 rotated, thus causing the coöperating members 6 and 12 to cut the glass and in the instance of bottles sever the capped end of the neck from the remainder thereof. It will be understood that during the cutting operation the member 9 may be manipulated for pressing the cutting element 12 gradually to its work, and, further, that owing to the cutting element 12 being sustained for movement with the member 9 the device may be 60 conveniently adjusted for tubes of varying sizes.

In the form of device illustrated in Fig. 2 the cutting elements 6 are journaled in bearings 5, fixed on the lower portion of an open 75 substantially rectangular base-frame 13, in the upper portion or bar of which there is threaded an adjustable member or screw 14, provided at its outer end with a hand-piece 15 and having its inner end swiveled, as at 80 16, in an adjustable member or bar 17, slidably disposed within the frame and provided with a bearing 18, in which the cutting element 12 is journaled, it being noted that in operation the tube to be cut is disposed on the 85 members 6 and the member 17 thereafter moved downward through the medium of the screw 14 for pressing the cutting element 12 to its work, as in the instance of the device above described.

Having thus described my invention, what I claim is—

In a device of the class described, a base-plate and a vertically-movable lever pivotally connected therewith, a pair of spaced 95 bearings fixed on one of the parts, glass-cutting members journaled in said bearings, a glass-cutting member carried by the other of said parts and adapted for coöperation with the first-named members, and means for 100 guiding the lever in its movements.

In testimony whereof I affix my signature in presence of two witnesses.

NILS A. LYBECK.
